UNITED STATES PATENT OFFICE.

EDWARD J. GULICK, OF ELKHART, INDIANA, ASSIGNOR TO C. G. CONN. LTD., OF ELKHART, INDIANA, A CORPORATION OF INDIANA.

DESIGN FOR A VALVE-CASING FOR A HORN.

58,226.

Specification for Design.

Patented June 28, 1921.

Application filed January 13, 1921. Serial No. 437,098. Term of patent 14 years.

To all whom it may concern:

Be it known that I, EDWARD J. GULICK, a citizen of the United States, residing in the city of Elkhart, county of Elkhart, Indiana, have invented a new, original, and ornamental Design for a Valve-Casing for Horns, of which the following is a specification, reference being had to the accompanying drawing, forming a part hereof.

On the drawing, Figure 1 is a side elevation of the valve casing showing the top and bottom caps and finger tip mounted

thereon; Fig. 2 is a top plan view; and Fig. 3 is a bottom plan view, which views clearly illustrate my new design for a valve casing for horns.

I claim:

The ornamental design for a valve casing for a horn, as shown.

In testimony whereof I have hereunto affixed my signature this 11th day of January, 1921.

EDWARD J. GULICK.
